[57] CLAIM

The ornamental design for an electrosurgical pencil with rocker arm actuator, as shown and described.

DESCRIPTION

FIG. 1 is a perspective view of an electrosurgical pencil with rocker arm actuator showing our new design;
FIG. 2 is a left side elevation view thereof with the right side elevation view being a mirror image thereof;
FIG. 3 is a top plan thereof;
FIG. 4 is a front view thereof;
FIG. 5 is a rear view thereof; and,
FIG. 6 is a bottom plan view thereof.
